Primary Examiner—Janice E. Seeger*Attorney, Agent, or Firm*—Terry M. Gernstein**[57] CLAIM**

The ornamental design for a display board for sequentially arranged pictures, as shown and described.

DESCRIPTION

FIG. 1 is a front, top and side perspective view of the display board for sequentially arranged pictures showing my new design;

FIG. 2 is a front elevational view thereof;

FIG. 3 is a rear elevational view thereof;

FIG. 4 is an end elevational view thereof, the end opposite being a mirror image of the end shown in FIG. 4; and,

FIG. 5 is a top plan view thereto, the bottom view being a mirror image of the top view shown in FIG. 5.

FIG. 1

FIG. 2

FIG. 5

FIG. 3

FIG. 4
